DESIGN FOR A HINGE

Peter Madri, Ozone Park, N. Y.

Application November 29, 1933, Serial No. 49,891

Term of patent 3½ years

To all whom it may concern:

Be it known that I, PETER MADRI, a citizen of the United States, residing at Ozone Park, in the county of Queens and State of New York, have invented a new, original, and ornamental Design for a Hinge, of which the following is a specification, reference being had to the accompanying drawing, forming part thereof.

Figure 1 is a front elevational view of a hinge, showing my new design, Figure 2 is a side elevational view thereof, and Figure 3 is a top plan view of the same.

I claim:

The ornamental design for a hinge, substantially as shown.

PETER MADRI.
